UNITED STATES PATENT OFFICE

VICTOR H. McENTIRE, OF GREENVILLE, PENNSYLVANIA

DESIGN FOR A THREE-SPOKE STEERING WHEEL FOR AUTOMOBILES

Application filed October 1, 1930. Serial No. 37,098. Term of patent 14 years.

To all whom it may concern:

Be it known that I, VICTOR H. McENTIRE, a citizen of the United States of America, residing at Greenville, in the county of Mercer and State of Pennsylvania, have invented a new, original, and ornamental Design for Three-Spoke Steering Wheel for Automobiles, of which the following is a specification, reference being had to the accompanying drawings, forming a part thereof.

Figure 1 is a plan view of the article showing my new design.

Figure 2 is an edge elevation illustrating the same.

I claim:—

The ornamental design for a three-spoke steering wheel for automobiles as shown.

VICTOR H. McENTIRE.
